UNITED STATES PATENT OFFICE.

WILLIAM F. GAUDIAN, OF DALLAS, TEXAS.

WALL CONSTRUCTION.

Application filed December 10, 1924. Serial No. 755,013.

This invention relates to wall constructions for buildings of any size and has for its object the provision of a device in which metal up-rights are positioned in spaced relation having integral lugs supporting a reinforcing wire mesh screen along one edge and a metal lath at the other edge for binding respectively a concrete wall and an inner wall as a unitary structure.

10 A further object of the invention is the provision of movable plates cooperating with metal up-rights for forming a removable wall for the inner face of a concrete wall incorporated about the outer projecting edges of the up-rights.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the 25 invention as expressed in the appended claims.

In the drawings:

Figure 1 is a view in perspective showing a wall in the process of construction and in 30 accordance with the principles of my invention.

Figure 2 shows a horizontal section of the same.

Referring more particularly to the drawings, 1 designates a plurality of vertically disposed steel up-rights which are mounted in position in any approved manner. These up-rights are provided along their vertical edges with flanges 2 and 3, thereby forming 40 a U-shaped steel beam. The flanges where connected to the up-rights 1 are provided with lugs 4 cut from the metal of the beam and lugs 5 are provided along the outer vertical edges of the flanges 2.

45 When the beams are in position and in proper spaced relation a coarse wire mesh screen 6 is secured to the outer vertical edges of the beam and held in place by inserting certain of the horizontally spaced wires of the screen 6 between a lug 4 or 5 and the adjacent metal of the up-rights. If desired the lugs may be hammered into position against the inserted wires for rigidly locking the screen to the beams.

The outer section of the building construction is a solid band of reinforced concrete 8 55 four inches thick which is continuous all around the building. The outer face of the wall of the building is covered by a thin coating 7 of stucco. The inner portion of 60 the concrete wall 8 embraces the outer edges of the uprights 1. Where bricks are employed as the facing of the outer wall 8 they are placed in close association with the wire screen 6 and beyond the outer flanged 65 edges of the uprights or studs 1. An outer form wall is temporarily secured in spaced relation with the outer edges of the studs for retaining the concrete until the same has hardened. When bricks provide a veneer 70 they may be utilized as the mould form for retaining the concrete during pouring.

A metal lath 15 is hung upon the splinters or cut lugs 4 and 5 and the inner coat of 75 plaster is applied to the metal laths. If desired, the lugs 4 and 5 may be hammered in order to lock the metal laths in place.

It will be seen by this construction that a rigid and substantial wall is formed having 80 an air space as shown at 16 between the inner face of the wall 8 and the inner face of the metal lath 15 and between the adjacent parallel clamps or uprights 1.

The perforations 10, after the wall 8 has been formed, provide a means through which 85 conduits may be passed for supplying the various needs of the building with water, gas, electrical energy or any other element usually employed. The diameter of the 90 perforations are such as to meet all the requirements. Reinforcing elements may be inserted through the perforations 10 when required. Further perforations 17 are formed in the uprights through which nails or other anchoring means are inserted for 95 securing wood strips or purlines.

What I claim is:

1. A wall construction, spaced metal up-rights, a wire screen secured to the edges of the uprights, a wall formed of concrete having the screen and vertical portions of the uprights embedded in said wall, a second wire screen secured to the opposite edges of the uprights and a composition cement embedded in the second mentioned wire screen 100 and spaced from the inner face of the concrete wall.

2. A wall construction, spaced metal up-

rights, a wire screen secured to the edges of the uprights, a wall formed of concrete having the screen and vertical portions of the uprights embedded in said wall, a second wire screen secured to the opposite edges of the uprights and a composition cement embedded in the second mentioned wire screen and spaced from the inner face of the

concrete wall, the uprights along their opposite vertical edges being provided with ¹⁰ lugs cut from the metal of the uprights and adapted to receive portions of the wire screen for supporting the wire screen on the uprights.

WILLIAM F. GAUDIAN.
